UNITED STATES PATENT OFFICE.

MAX E. SCHMIDT, OF CONVENT, NEW JERSEY.

TRACTION DEVICE

939,334.

Specification of Letters Patent.

Patented Nov. 9, 1909.

Application filed October 28, 1908. Serial No. 459,852.

To all whom it may concern:

Be it known that I, MAX E. SCHMIDT, a citizen of the United States, and a resident of Convent, Morris county, State of New Jersey, have invented certain new and useful Improvements in Traction Devices, of which the following is a specification, reference being had to the accompanying drawings, in which—

10 Figure 1 is a diagrammatic top view of parts of an endless carrier embodying one form of my invention; Fig. 2 is a side view of parts on enlarged scale; and Fig. 3 a vertical section on the line 3—3 of Fig. 2.

15 My present invention relates particularly to that class of carriers, described in U. S. Letters Patent No. 747,090 granted to me and G. A. Mayland December 15th, 1903, which consists of a series of unitary members or carriers sequentially coupled to constitute a substantially continuous moving platform propelled by the rotation of a series of wheels disposed beneath the same and upon the treads or peripheries of which

20 the said carriers are supported upon rails secured to the latter, the treads of which rails are downwardly presented and disposed, so as to bear upon and coat with the treads of said wheels in such manner that

25 the rotation of the latter causes the said rails, with their connected carriers, to advance with approximately the same speed of movement as the peripheries of said wheels.

30 Since my said patent was granted, my researches have disclosed that it is important for the full development and successful application of the required tractive force to the running gear of an endless conveyer, that substantially all of its supporting wheels

35 should be positively rotated. If, for instance, the driving wheels are placed in the running gear a given distance apart, each one of said wheels, or groups of wheels, must develop sufficient tractive force to move a

40 length of the conveyer of the given distance, to accomplish which various devices have been hitherto resorted to, added weights for instance to increase friction, and thus traction, between the parts contacting and

45 moving relatively to each other.

50 The object of my present invention is to provide means whereby the total propulsive force required to move the conveyer may be successfully and uniformly distributed at a plurality of points, the number of which is practically indefinite, and there so imparted

as to increase the aggregate tractive power developed and thereby insure at all times steady and equal progression in the running gear of the endless conveyer without resort to additional weights or other devices.

It will be noted that in carriers of the "moving platform" type referred to, the unitary members or carriers constituting such platform are each, taken separately, of relatively moderate weight as compared to the aggregate weight of the entire platform taken as a whole. Consequently very considerable power is required to propel the entire platform, as compared to one of its units. Such power is necessarily the resultant of the amount of propulsive force applied to rotate the smooth faced driving wheels and the amount of pressure or tractive force with which the downwardly presented treads of the rails of the unitary carriers bear against said driving wheels. In other words, the propulsion of the platform depends upon the weight thereby brought to bear upon the propelling wheels, *i. e.* upon the aggregate adhesion of said smooth faced propelling wheels against the treads of its said rails.

In the type of device referred to, the aggregate combined weight of all the unitary carriers cannot be concentrated at any given point, or points, and the propulsive force to move the platform can therefore not be applied at such point, or points, in conjunction with the tractive force which would develop from the adhesion obtained from such a concentration of weight. In previous constructions this has caused difficulties, and my present invention comprises an expedient whereby these are overcome. By my present device it is possible to produce effects similar to those resulting from such concentration as aforesaid. This I accomplish by multiplying the number of driving wheels actuated by one, and the same, motor and disposing them so as to support, not as heretofore a single unit of the platform, but simultaneously a plurality of said units, thus combining with the propulsive force of said single motor the aggregate weight, adhesion and consequent tractive force, of many units, instead of one. For example, assume that, as in previous constructions, the pairs of wheels actuated positively by motors are one hundred feet apart, the platform being intermediately supported on intervening pairs of idler wheels say ten feet apart and the

unitary carriers being each ten feet long. It is apparent that in such case the tractive force brought to bear upon each pair of wheels, while positively actuated by a motor of given denomination, will be such as may be developed from the weight of the single unitary carrier then tracking with said pair of driving wheels. If now, as per my said invention, say four pairs of said idler wheels, two on each side of said actuating pair, be geared with the latter so that the entire group are also rotated positively by said motor then there will be applied to the propulsive force of the latter, less an unimportant loss through friction, the combined weight, adhesion and consequent tractive force of five, instead of one of said unitary carriers. I am thus enabled to multiply tractive force, without materially increasing power. I accomplish this object by the devices hereinafter described which comprise, broadly speaking, means for imparting from a common source of power to a series of supporting wheels, not only positive but also synchronous rotation.

Referring now to the drawings, *l*, *l*, are pillars or stationary supports in which are journaled rotatable shafts *k*, carrying fixed thereto wheels *w*, which support and propel the tracks *b*, secured to each unitary carrier *p*, of the series constituting the endless carrier or moving platform. These tracks, *b*, it will be observed, have their treads downwardly presented and bearing upon the peripheries of the wheels *w*. Each of said unitary members is coupled to the preceding and following one in any convenient manner as preferably by coupling pins *e*, engaging with link *d*, secured to each preceding unitary carrier. Means are provided to insure against transverse displacement, as for instance downwardly extending projections *n*, preferably extensions of pin *e*, which travel within continuous guide rails *g* supported stationarily by braces *h*, friction being preferably relieved by friction rollers *f*, or other means shown in said patent may be employed.

j represents diagrammatically means for applying power to rotate shaft *k*, in this instance an electric motor. It will be obvious that as shaft *k* is rotated the tractive force thereby imparted to the supporting wheels *w* will propel in turn each unitary carrier *p* in the direction of rotation, and that such carrier will also be supported as against transverse displacement by the downwardly extending projections *f* engaging in the endless stationary tracks *g*. None of the foregoing parts referred to by letter constitute any part of my present invention unless as elements in combination, they being substantially the same as those heretofore described in my said Letters Patent No. 747,090.

My present invention comprises for the purposes aforesaid the application to the said devices of means for transmitting rotation synchronously from each power shaft *k* to other shafts *k'* and their appurtenant supporting wheels *w'* and to this end, and as one means of embodying my said invention, I secure to said shaft *k* and to each shaft *k'* sprocket wheels *A*, *A'*, rotated simultaneously and synchronously with the wheels *w*, *w'*. It will be observed that the said wheel bearing shafts are mutually parallel; also that the said sprocket wheels carried by each shaft are in alinement with the corresponding wheels carried by the neighboring shafts. An endless chain *B* is operatively connected with two of the sprocket wheels, in alinement, of each adjacent pair of shafts. By their aforesaid connection each of the shafts is caused to rotate positively and at the same time synchronously with those shafts to which power is directly applied as aforesaid and the entire series of parallelly disposed shafts is likewise rotated so that each member of the running gear thus connected transmits and delivers to the load, at the various points of contact, tractive force simultaneously and in substantially equal degree.

I have further devised means for continuing the aforesaid connecting of the shafts to embrace portions of the course separated by curves. This with special reference to the type of conveyer described in said U. S. Patent 747,090. As an illustration of one of such means the shafts *J* and *K'* (Fig. 1) are shown extended and operatively connected by the gears *G* *G'*. It is preferable that such extended or transmission shafts, as they may be termed, should each be positively actuated by a motor *j* as shown. By this means the quality of tractive force and synchronism of rotation is mechanically secured between series of shafts separated by a curve in the course of the carrier. It will be understood that by suitably beveled gears, or other obvious mechanical means, the transmission of uniformity and synchronism of rotation may be transmitted at any desired angle instead of in parallelism as shown between the shafts *K*, *K'*, Fig. 1, merely for illustration; also that means other than sprocket wheels and chains specifically may be employed to secure synchronism of rotation, as for instance suitable trains of gears, etc.

In Fig. 1 the entire series of unitary carriers constituting the endless platform is not shown in order that sub-disposed members may be more clearly perceived. It will be understood however that, in operation, the unitary carriers *p* are sufficient in number to produce an endless chain thereof covering the entire system of supporting wheels *W*, *W'*, etc.

Referring now more specially to the

curved portions of said running gear the shafts K^2 of Fig. 1 represent idler shafts carrying idler wheels W^2 . The last mentioned shafts and wheels are supported identically as the wheels and shafts w and k , except that they are, as stated, idlers. By this means, in combination with the devices hereinbefore described, the endless carrier and its unitary members of the type of conveyers described in said Patent No. 747,090 are insured uniformity and steadiness of progression when progressing curvedly.

It will be understood that the novel means which I have described for increasing traction by as aforesaid insuring uniformity and synchronism of rotation in a plurality of shafts comprised in a power transmission device is applicable to other traction devices than that of the particular endless carrier above described.

I am aware that means have been employed to synchronize the rotations of a plurality of shafts provided with gear wheels engaging rack links to drive endless chains. I refer to devices sometimes designated "traveling stairways". In these devices said chains are connected with a plurality of trucks which carry the steps composing the stairway. Said trucks are supported on idler wheels tracking with stationary rails, none of said wheels being drivers. Such devices are, therefore, not "traction devices" in the sense of mine, and constitute no part of my invention, being distinguishable therefrom in that, among other things, the former are propelled only by direct engagement of said gear wheels with said rack links, and the weight of the running gear of the said "traveling stairways", including their said idler wheels, is at all times only a dead load upon the propulsive force employed, instead of, as per my invention, utilized in part to coact therewith in promoting propulsion, whereby I am enabled to dispense with the said previously required direct connection of said endless chains with my unitary carriers, and thus realize what may be properly termed a traction device.

Having now described my invention, what I claim as new and desire to secure by Letters Patent is the following, viz:—

1. A traction device comprising an endless platform composed of a plurality of coupled-together unitary carriers provided with underneath rails having downwardly presented treads, a plurality of shafts rotatable in stationary bearings and provided

with wheels upon which said treads bear for support and propulsion of said platform, means for imparting rotation to some of said shafts, and means for transmitting rotation therefrom to others of said shafts.

2. A traction device comprising an endless platform composed of a plurality of coupled-together unitary carriers provided with underneath rails having downwardly presented treads, a plurality of mutually parallel shafts rotatable in stationary bearings and provided with wheels upon which said treads bear to progress straightly, means for imparting rotation to some of said mutually parallel shafts, means for transmitting rotation therefrom synchronously to others of said mutually parallel shafts, and, interposed between groups of said parallelly disposed shafts radially disposed shafts provided with idler wheels upon which said treads bear to progress curvedly.

3. A traction device comprising an endless platform composed of a plurality of coupled-together unitary carriers provided with underneath rails having downwardly presented treads, a plurality of shafts rotatable in stationary bearings and provided with wheels upon which said treads bear for support and propulsion of said platform, means for imparting rotation to some of said shafts, sprocket wheels in mutual alignment and rotated by consecutive pairs of said shafts, and endless chains operatively engaging with said sprocket wheels to transmit rotation synchronously from one to another of said shafts.

4. A traction device comprising a plurality of independent, coupled-together, unitary carriers, supporting rails, a plurality of smooth faced bearing wheels tracking with said rails to support each said carrier respectively, a motor, means to transmit power from said motor directly to some of said wheels to positively rotate them while supporting one of said carriers, and means to transmit power from said motor to positively rotate others of said wheels while supporting others of said carriers, substantially as and for the purposes described, whereby traction opposed to said motor is increased, substantially as and for the purposes described.

MAX E. SCHMIDT.
